CHAIR FOR CONCRETE STRUCTURES.

1,356,315.

Specification of Letters Patent. Patented Oct. 19, 1920.

Application filed June 12, 1919. Serial No. 303,551.

To all whom it may concern:

Be it known that we, EDSON M. SCOFIELD and LYNN M. SCOFIELD, citizens of the United States, residing in Chester Valley, Pennsylvania, and San Diego, California, respectively, have invented Chairs for Concrete Structures, of which the following is a specification.

One object of this invention is to provide 10 a chair for temporarily supporting the reinforcing members of a concrete structure, which shall be of such composition as to neither rot nor become corroded after being incorporated in the finished structure and 15 which shall be particularly adapted for properly holding the reinforcing elements in predetermined positions relatively to wooden or other forms or to each other during the pouring of the concrete;—the invention 20 contemplating a chair which shall not only make a perfect bond with the concrete but which shall be mechanically tied or held within the same so as to prevent access of water to the interior of the finished structure and more particularly to the reinforcing 25 elements therein.

We also desire to provide a chair of the general type above indicated which shall include novel means whereby it may be held 30 in the desired position within a form and which also shall possess improved means for holding one or more reinforcing elements in definite positions.

These objects and other advantageous 35 ends we attain as hereinafter set forth, reference being had to the accompanying drawings, in which,

Figure 1 is a fragmentary vertical section 40 of part of a reinforced concrete structure with its forms, showing different modifications of our invention as applied thereto;

Fig. 2 is a side elevation, partly in section, illustrating a simple form of our invention;

Fig. 3 is an elevation partly in section 45 showing our invention as adapted for use on a vertical form surface;

Fig. 4 is a side elevation, partly in section, showing our chair as designed to support two reinforcing elements at right angles to each other;

Fig. 5 is a plan of the structure shown in Fig. 4;

Fig. 6 is a side elevation partly in section, illustrating our invention with special means whereby it may be positively held to 55 a form; and

Fig. 7 is a side elevation partly in section illustrating a modification of the invention designed to space two substantially parallel 60 reinforcing elements.

In making reinforced concrete structures it is necessary that the reinforcing bars or elements shall be spaced within the forms in such manner that they will extend at definite distances from the same as well as 65 from each other in order that they may be embedded in the desired positions in the finished concrete structure. For thus positioning these elements it has hitherto been customary to employ various types of holding devices or chairs which were either made of metal, and were therefore subject to corrosion, or were made of wood or other material liable to rot. As a result channels or passages were formed in the finished concrete structure through which it was possible 70 for water to gain access to and cause corrosion of the reinforcing elements. 75

In order to prevent this objectionable action and the consequent weakening of the 80 reinforced structure resulting therefrom, we provide, in one of the simpler forms of our invention, concrete chairs of the form and construction shown in Fig. 2. These each consist of a generally cylindrical concrete 85 body 1 having flat ends and formed with an annular depression or groove 2 in its cylindrical surface, usually about midway between the ends. One of the latter, in this form of the invention, is provided with a 90 transverse depression 3 for the reception of a reinforcing bar 4 which is held in place by a tie wire 5 embedded in the body of the chair so that its two ends project from the flat face thereof on opposite sides of said 95 recess 3. Such a chair is particularly adapted to support reinforcing bars at definite distances from a form 6 and it is obvious that a mass of concrete surrounding the chair will form a perfect bond therewith as 100

- well as mechanically hold the same from movement owing to its entrance into the depressions or recesses 2 and 3, particularly the former. In case it should be desired to 5 employ chairs constructed according to our invention for the purpose of maintaining reinforcing rods at definite distances apart, they would be formed with transverse recesses or depressions 3 in both of their flat 10 faces or ends as illustrated at 7 in Fig. 1 and with a second tie wire 5 embedded in each of them, in a manner similar to that shown in Fig. 2, for the purpose of positively holding the second reinforcing bar 4. 15 If desired or found necessary, as when the chair has considerable length as shown in Fig. 7, more than one of the annular recesses 2 may be provided.

While in some cases the wire tie 5 may be 20 depended on to properly hold the chair with one of its faces flat against the flat form surface even though this should be vertical rather than horizontal, we may if desired or found advisable, render impossible movement of the chair relatively to the form, and for this purpose construct such chair as shown in Fig. 6. In this case the body or main portion 1^a of the chair is of a construction similar to or identical with that 25 shown in Fig. 2 but that face opposite the one having the transverse depression 3 is made with a cylindrical or other extension 9 of such a length as to project completely through the form 6. The outer end of this 30 extension is formed with a transverse slot for the reception of a key 10 so that it is possible to draw the body 1^a tightly against the form and maintain it immovably in such position. After the body of concrete 11 has 35 set, the keys 10 are removed in order to permit of the removal of the forms, and the extensions 9 are then knocked off.

In Figs. 4 and 5 we have illustrated a 40 form of chair 1^b which is especially designed to positively hold in place two reinforcing elements 4 and 11 running at right angles to each other, and for this purpose that end of each chair opposite the one designed to engage the form has two trans- 45 verse intersecting depressions or recesses 3 and 3^a extending at the desired angle to each other, the recess 3^a being materially deeper than the recess 3 so that the bar 11 may be carried below but practically in contact with 50 the bar 4. As an alternative means for holding the chair to the substantially vertical or other form surface, we may embed in that portion of its body adjacent the end designed to engage the form, a length of 55 wire or equivalent material 12 designed to be held to the form 6 by staples or nails 13. This, as well as the other form of our invention, is preferably provided with one or more of the annular grooves 2 and has one 60 or more recesses or depressions formed in

its outer end or face for the reception of a reinforcing bar or bars. In case two of the latter are to be spaced as shown in Fig. 4, the tie wire 5 is so mounted in the body of the chair as to extend diagonally across the 70 superposed bars as shown in Fig. 5.

By the use of chairs of the construction above described the reinforcing bars are supported and held in place during the pouring of the concrete and until the finished 75 structure is completed. By reason of their composition these chairs are non-corrosive and durable, and being of a material similar to that composing the body of the finished structure, are not subject to material 80 disintegration or loss of strength, as they become an integral part of the concrete in which they are embedded. In addition, by reason of the annular groove or grooves with 85 which they are formed, our chairs are mechanically keyed or locked to the structure in which they are used so that there is not only a complete prevention of penetration of water or other destructive material to the interior of the structure and a consequent freedom from deterioration of the reinforcing elements but the chairs are immovably held in place. Prior to and during the pouring of the concrete the reinforcing bars are mechanically bound to the 90 chairs by the tie wires and are so held in the recesses of said chairs that their shifting or displacement is a practical impossibility.

We claim:

1. As a new article of manufacture a chair for concrete construction consisting of a substantially cylindrical body of concrete, having a recess in one end for the reception of a reinforcing bar, and a wire embedded in the body of said chair and projecting on opposite sides of said recess for holding such bar in place, there being an annular recess in the cylindrical body of the 105 chair.

2. As a new article of manufacture a molded concrete chair having a recess for the reception of a reinforcing bar and including an elongated stem for insertion in a 110 form.

3. As a new article of manufacture a molded concrete chair having an extension of reduced cross section for insertion in a form.

4. As a new article of manufacture a 115 molded concrete chair having an extension for insertion in a form; with a key engaging said extension to lock the chair to the form.

5. As a new article of manufacture a 120 chair consisting of a molded body of concrete provided with a plurality of transverse intersecting recesses for the reception of reinforcing bars and having an annular recess in a plane parallel with that of said 125 130

first recesses for the reception of the concrete in which it is embedded.

6. A new article of manufacture consisting of a molded concrete chair of substantially cylindrical form having an annular depression in its cylindrical surface and having at least one transverse depression in

an end for the reception of a reinforcing bar.

In witness whereof we affix our signatures.

EDSON M. SCOFIELD.

LYNN M. SCOFIELD.
